E. R. MARTIN

COLLAPSIBLE CRATE

Filed June 3, 1922

Inventor

EDGAR R. MARTIN.

By N.E. Gee

Attorneys

UNITED STATES PATENT OFFICE.

EDGAR R. MARTIN, OF ALTOONA, PENNSYLVANIA.

COLLAPSIBLE CRATE.

Application filed June 3, 1922. Serial No. 565,554.

To all whom it may concern:

Be it known that EDGAR R. MARTIN, a citizen of the United States, residing at Altoona, in the county of Blair and State 5 of Pennsylvania, has invented certain new and useful Improvements in Collapsible Crates, of which the following is a specification.

This invention relates to collapsible 10 crates and the like that are extensively used to transport merchandise, eatables, poultry and a variety of articles, and has for its primary object an improved construction whereby the crates may be readily folded to 15 occupy a minimum space.

Another object of this invention is to provide means whereby the ends of the crate are each provided with a plurality of slide- 20 able cross bars, the ends of which are adapted to be attached to the top and bottom portions of the crate, said cross bars each having a common pin connection in the center thereof.

With these and other objects in view 25 which will be more readily apparent as the nature of the invention is better understood, the same consists in the novel construction, combination, and arrangement of parts as will be hereinafter fully pointed out, illus- 30 trated and claimed.

It will be understood by those skilled in the art to which this invention belongs that the same is susceptible of structural changes and modifications without departing from 35 the spirit or scope of the invention, but a preferred and thoroughly practical embodiment of the invention is shown in the accompanying drawings, in which:

Figure 1 is a plan view of my improved 40 collapsible crate or coop in an extended position.

Figure 2 is a side elevation of the crate shown in Figure 1 of the drawings.

Figure 3 is an end view of the crate as 45 shown in Fig. 1.

Figure 4 is an end view of the crate as it appears in a collapsed position.

Figure 5 is a detail view showing the top raised from the bottom, the side members 50 being shown folded as they appear in a collapsed position.

Figure 6 is a detail section through an end of the crate and illustrates the manner in which the end is swung into position 55 when folded.

Figure 7 is a plan view of the collapsible

brace bars and illustrates the common pivot pin connection used in conjunction with both bars.

Figure 8 is an edge view of the bars 60 shown in Figure 7 of the drawings.

In the following description similar reference numerals refer to similar parts throughout the several figures of the drawings.

In carrying out this invention I provide a collapsible crate that will fold together so as to occupy a minimum amount of space, and this collapsible feature is made possible through the use of cooperating paired ex- 70 tensible and contractible slotted bars one of which is designated by the numeral 10, and the other by the numeral 11. One pair of such bars are provided at each end of the coop and are arranged in operative relation 75 as shown in Figure 3 of the drawings.

Each bar 10 and 11 is preferably made in two pieces designated by the numerals 12 and 13, and each of these pieces or sections is provided with a slot 14 which is adapted 80 to receive a pin 15 carried by the opposite section and in alinement with the slot. Where the bars 10 and 11 cross and the slots 14 register, they receive a common pin 16 which is adapted to slide in the slot when 85 opening or closing the crate. When the crate is in its extended position as shown in Figures 1 and 2 and 3, the pins 15 and 16 occupy a position adjacent each other while in the collapsed position the pins 15 are 90 carried away from the pin 16 by the bar to which they are attached. The units must obviously get shorter as the crate collapses.

The ends 17 and 18 on each of the sections 12 and 13 are pivoted to the top 95 and bottom 20 of the crate as shown in Figure 3 of the drawings, and when the crate is opened or closed the sections fulcrum on the pins 21 and 22 positioned in the top and bottom members of the crate. 100

The crate also includes in addition to the top and bottom members 19 and 20, side members S, each of which is hinged to the bottom member 20 as shown in Figure 5 of the drawings, and are adapted to be swung into position when raising the crate from its collapsed position. The manner of making the end members E is shown in Figure 6 which illustrates the said ends thrown up against the top from the position which 110 they occupy when the crate is in its extended position.

From the foregoing it will be apparent that the crate consists of top, bottom, side and end members which are hingedly connected, while the opposite edges of the top 5 and bottom members 19 and 20 are connected by the extensible cross-braces 10 and 11. The cross-braces 10 and 11 serve mainly to anchor or tie the top and bottom members or walls 19 and 20 to which the side 10 members S and end members E are hingedly connected by the hinges H.

I claim:—

In a collapsible crate having top and bottom members, and side and end members 15 hinged thereto, a pair of cross-bars con-

nected at their opposite ends respectively to the top and bottom members, each of said bars including separate sections having registering slots, a pin projecting from the inner face of each section and slidably engaging the slot of the adjacent section whereby when the sections are extended the pins of the four sections of the crossing bars draw close together to rigidly brace the bars, and a pivot pin common to both bars and 20 located where the slots thereof register. 25

In testimony whereof he affixes his signature.

EDGAR R. MARTIN.
